(57) **CLAIM**

The ornamental design for a shaft attaching and detaching device, as shown and described.

DESCRIPTION

FIG. 1.1 is a perspective view of a shaft attaching and detaching device showing our new design;

FIG. 1.2 is a front view thereof, the left side view, the right side view and the back side view being omitted as being identical with the front view, respectively;

FIG. 1.3 is a top view thereof;

FIG. 1.4 is a bottom view thereof;

FIG. 1.5 is a perspective view showing detaching; and

FIG. 1.6 is a perspective view showing attaching.

The broken lines are shown for the purpose of illustrating parts of the article that form no part of the claimed design.
